Application July 8, 1941, Serial No. 401,460

23 Claims. (Cl. 62—1)

This invention relates to a system for converting a liquefied gas into a vapor for industrial use, and more particularly to a system adapted to be installed at a consuming plant for storing and converting liquid oxygen into gaseous oxygen whenever desired.

The invention has for its object generally the provision of an improved construction and arrangement of component devices for quickly and expeditiously converting a quantity of liquefied gas, such as liquid oxygen, into gaseous material at a relatively high pressure.

More specifically, the invention has for its object the provision of an improved system for storing and converting liquid oxygen into gaseous oxygen at a relatively high pressure, while at the same time maintaining the storing device at a relatively low pressure.

Another object is to provide a system of the character indicated with transfer pumps so located with respect to the liquid storing device as to effect the transfer of liquid to and from the same, when desired, in a relatively short space of time.

Another object is to provide a system of the character indicated with storage means of relatively large capacity and relatively small losses and arranged with respect to the other devices in the system in a manner which permits charging the same with relatively large amounts of liquid and at relatively infrequent intervals if feasible.

Another object is to provide a system of the character indicated with means connected thereto in a manner which incorporates a reservoir for oxygen either in the liquid phase or in the gas phase at high pressure, in order that a response may be had substantially instantaneously to demands for oxygen. The reservoir when provided with a connection into the system as disclosed so that it is in constant fluid communication therewith may be said to be floatingly connected into the system.

Still another object of the invention is to provide a system of the character indicated in which the storage means is so arranged that the stresses imposed on the system by the oxygen gas at high pressure are not impressed on the liquid storing means.

Other objects of the invention will in part be obvious and will in part appear hereinafter.

The invention accordingly comprises the features of construction, combination of elements, and arrangement of parts, which will be exemplified in the construction hereinafter set forth,

and the scope of the invention will be indicated in the claims.

For a fuller understanding of the nature and objects of the invention reference should be had to the following detailed description taken in connection with the accompanying drawings, in which:

Fig. 1 is a view, partly in section and partly in elevation, showing a system having floating means for holding liquid oxygen and adapted for intermittently dispensing oxygen in accordance with the invention;

Fig. 2 is a similar view showing a modified type of system having floating liquid holding means provided in accordance with the invention;

Fig. 3 is a similar view showing another modified system having floating gas holding means provided in accordance with the invention; and

Fig. 4 is a similar view of still another modification in which floating gas holding means or receivers are provided in accordance with the invention.

Referring now to the drawings, and particularly to Fig. 1, 10 denotes the inner vessel of a heat insulated storage container 11 adapted to hold a body or charge of liquid oxygen which is deposited therein from any convenient source of supply, such as a transport container or tank car. Such storage container is preferably of relatively large capacity and has a liquid supply and withdrawal connection 12 communicating with a point closely adjacent to or at the bottom of vessel 10. The connection 12 is shown as controlled by a pair of valves 12' and 12'' and leading from the outlet of a transfer pump 13 which is preferably disposed below the storage container and has an inlet connection 14 that terminates in a coupling 15 to which a service connection leading from a transport container (not shown in the drawings in the interests of clearness of illustration) is adapted to be attached. Associated with the connection 12 there is a branch 12x that is valve controlled and is adapted to be coupled by another connection that leads to the gas space of the transport container for priming purposes. A connection 12³, controlled by a valve 12⁴ and leading to the top of vessel 10, may be provided when desired.

Liquid withdrawal from the storage container, as well as liquid introduction, may be advantageously accomplished through the connection 12. Accordingly, it is shown tapped by a connection 16 having a valve 16' and leading to the inlet of a pipeline pump 17.

Both pumps 13 and 17 in this embodiment of the invention are preferably of the rotary type. The pump at 13 is required to pump only against a head of pressure which is substantially a gravity head and hence may be a single-stage turbine type pump of the character disclosed in application, Serial No. 345,308, filed July 13, 1940 in the name of O. A. Hansen which issued February 1, 1944, as Patent No. 2,340,747. That at 17 is required to pump against heads of materially greater values and is hence advantageously a multi-stage turbine type pump of the character disclosed in application, Serial No. 388,048, filed April 11, 1941, in the names of Zenner & Yendall which issued February 1, 1944, as Patent No. 2,340,787.

A discharge conduit 18 having therein an automatic priming valve 19 leads from the outlet of pump 17 through a portion 18' to the gas space of the vessel 10. A conduit 20, having therein a check valve 21, is tapped into the conduit 18 at a point preferably in advance of valve 19. A control valve, as shown at 21', is also preferably introduced in the conduit 18 for the purpose of adjusting the time response of valve 19. Such valve can be so set that valve 19 is responsive to the pressure in conduit 18 and causes valve 19 to close a short time after the pump 17 is started. Thus when pump 17 is idle and for a brief interval after it has started, valve 19 opens and the pump primes by recirculation back to container 10 by way of branch 18'. As soon as liquid passage is established, the pressure rise in conduit 18 causes valve 19 to close and the discharge from pump 17 must thereafter pass out by way of conduit 20 through check valve 21.

The conduit 20 is preferably branched as shown at 22 and 22' which lead in parallel to a depending portion 22x that feeds into an auxiliary container 24 at the top. Branch 22 has therein a heating coil 23 while branch 22' has a back pressure valve 25 normally closed but arranged to open upon the attainment of a predetermined high pressure in the container 24 so as to permit the discharge of cold liquid along with heated material directly into the container 24 and thereby reduce the pressure therein. Such container is advantageously constructed with a materially less capacity than the container 11.

The liquid, when introduced into the container 24 as here proposed, is substantially a saturated liquid at a relatively high pressure. Such liquid is arranged to be withdrawn when desired from the auxiliary container and supplied to suitable vaporizers. To this end, a connection 26 that leads from a point relatively close to the bottoms of container 24 is provided and leads to a second heating coil 27. A gas phase connection 28 is also preferably provided and arranged to lead from the gas space of the auxiliary container into a third heating coil 29. The coils 23, 27, and 29 are supplied with suitable heating medium, either separately or collectively. A common heater casing for the purpose of heating them collectively is indicated in the drawing at H.

The outlets from coils 27 and 29 lead to a common service main 30 which has a regulating manifold 31, or equivalent device, connected therein, and is arranged to lead into a metering device, here symbolically indicated at 32. Any suitable metering device may be employed, for example, a conventional bellows meter.

The connection from coil 29 to the main 30 is provided with a back pressure valve 33 which

is arranged to open when the pressure in container 24 reaches a predetermined high value in order to effect preferential withdrawal of gas phase from the container 24 and thereby reduce the pressure therein. When the valve 33 closes, only liquid phase is withdrawn, by way of conduit 26, from the container 24.

The liquid level in the auxiliary container is preferably maintained between fixed limits and the maintenance advantageously accomplished automatically. The level indicating conduit 34 is accordingly provided with a liquid level controlled switch, shown diagrammatically at 35, which is connected through an electrical circuit shown diagrammatically at 17a to control the motor (not shown) that runs pump 17. By such arrangement the pump 17 may be started automatically whenever the liquid level in the auxiliary container falls below a desired point, and automatically stopped when the liquid level reaches a desired point. A safety valve 36, disposed at a convenient point, for example in communication with connection 28, operates to maintain the gas pressure in the container 24 at a desired value.

In operation, the system above described normally has gas under pressure substantially above atmospheric in the gas spaces of both containers 11 and 24. The pressure in container 11 is preferably only slightly above atmospheric, for example, 15 p. s. i. gauge. The pressure normally obtaining in container 24 is maintained at a value substantially above that in the pipeline, for example, 25 p. s. i. above that of the pipeline. The pressure in container 24 is, however, normally of a relatively low value, for example, 150 p. s. i. gauge. The pressure in the pipeline is normally of a value of from 100 to 125 p. s. i. gauge. The pressure in container 24 may rise to a relatively high value at times, due to heat leakage, for example, to a value of 400 p. s. i. gauge. This permits heat storage over an extended period without loss of gas phase through the safety valve 36. Such pressure is, of course, reduced as soon as withdrawal occurs, mainly that which takes place through conduit 28. The pressure of the gas in the service main is normally maintained at a constant pressure, for example, 100 p. s. i. gauge, due to the action of the pressure regulator at 31. In the event there is a demand for gas made on the service main, the regulator opens and gaseous oxygen flows from the coils in heater H to meet the demand. The gas pressure in the auxiliary container causes liquid to flow through the connection 26 into coil 27, while gas flows through the connection 28 into coil 29 as soon as pressure in the container is high enough to keep valve 33 open. If the demand continues, or if repeated until the level of the liquid in container 24 falls below the fixed point, the switch 35 will automatically start the pump 17 and liquid will be withdrawn from container 11 and elevated to the pressure to be maintained in container 24 and introduced therein through the conduit 22 and the depending connection 22x.

The gas material entering the container 24 by way of conduit 22 and connection 22x is in the vapor phase, since it has traversed the heating coil 23. This in turn produces a pressure rise in container 24 until the valve 25 opens. Gas material in liquid phase now enters container 24 by way of conduit 22' which branches off from the conduit 22 in advance of the heating coil 23. The material in the liquid phase thus supplied

is substantially at the pressure in the container 24 but by reason of its lower temperature causes condensation of vapor in container 24 which tends to reduce the pressure therein. When the pressure in container 24 has sufficiently dropped valve 25 automatically closes. An increase in the flow of material entering by way of coil 23 and conduit 22 now takes place and continues until a balance is achieved.

The check valve 21 in the connecting conduit 20 operates not only to pass readily the liquid being transferred by pump 17, but also to prevent the pressure values that obtain in the auxiliary container and the circuit 22 from building up in the connection to, or in, the gas space of container 11. In this way, a relatively low pressure is at all times maintained in the container 11, i. e., a pressure not in excess of 15 p. s. i. gauge, as above described.

The auxiliary container 24 is thus seen to be in constant communication with the supply line which may be considered as leading from connecting conduit 20. If this auxiliary container were made relatively large, such portion of the system from the auxiliary container on would be but a system of the kind commonly referred to as a "cold converter" system and disclosed in U. S. Patents Nos. 1,942,944 and 1,943,047, issued respectively in the names of Smith and Updegraff on January 9, 1934. By this attachment, there is always a sufficient supply of gas material maintained in reserve to meet instantaneously the relatively large demands for gaseous oxygen, such as occur in industrial plants, particularly in metal working plants. That this is so will be readily understood when it is noted that the liquid material in the auxiliary container is both at high pressure and nearly boiling.

When a charge of liquid is introduced into the container 11, supplied from a transport container that is shipped open to the atmosphere, a partial reduction of the pressure in container 11 takes place. During the periods when withdrawal of liquid phase from the container 11 takes place, the pressure therein is allowed to rise as this avoids loss of gas phase to the atmosphere on account of heat leakage. Each subsequent filling of container 11 effects a similar lowering of the pressure therein.

The economies obtained by this system are seen to be due to the fact that the large body of liquefied gas, such as is necessarily maintained at the plant in the container 11 in order to meet relatively large demands, is not at high pressure and may be cooled to some extent below its boiling temperature. Subcooled liquid may occur in connection with the small pressure increase arising from operation of pump 13 to supply fresh additions of liquid to container 11. The connection 12³ and its valve 12⁴ enable the fresh additions of liquid to be discharged preferably into the top of container 11. The heat leakage through the insulation can be and preferably is reduced to a relatively low value by suitable means; for example, employing a finely divided insulating material in the insulating space which is evacuated as taught in the pending application, Serial No. 307,945, filed in the name of L. I. Dana on December 7, 1939.

In the modification shown in Fig. 2, the container 11 is indicated as arranged substantially in the same manner as in the system of Fig. 1. The pump connections, however, are different, the arrangement being of a character adapted

for relatively continuous operation of the pumps. Such operation is adapted to loads with less violent fluctuations than occur in systems ordinarily serviced by the arrangement of Fig. 1.

5 Here the connection 120, which leads from the bottom of vessel 10 in container 11, serves only as a liquid withdrawal connection. This connection has a control valve 12' and leads into conduit 14 that terminates with coupling 15. 10 This latter, as in the system of Fig. 1, is adapted to be connected through a flexible hose to receive a charge from a transport container. A valve 14' controls conduit 14. Hence it is seen that the conduit 120 and conduit 14 lead in 15 parallel to an inlet 131 of a first-stage pump 130. An outlet connection 161 leads from the pump 130 to a conduit 162 and has a branch 163 leading to the inlet of a second-stage pump 170. An outlet conduit 180 leads from pump 170 and communicates at its upper end with the gas space of vessel 10. Conduit 180 is controlled by a valve 181 and has a connecting conduit 200, leading from a point between the outlet from pump 170 and valve 181 to the supply circuit 22. 25 Conduit 200 has valves 201 and 202 to control it, the latter being a check valve. By the arrangement provided, it is seen that the pumps 130 and 170 operate in series. Pump 170 may, therefore, be a single-stage pump as well as that 30 at 130. This series operation takes place except when liquid is introduced to container 11; one such pump being sufficient for this service.

One end of conduit 162 connects with and discharges into conduit 180 at a point between the 35 container 10 and valve 181. The portion of conduit 162 which so connects with conduit 180 is controlled by a valve 162'. The other portion of conduit 162 that leads from the conduit 161 in the opposite direction to that having valve 162' 40 is also provided with a valve 162'' and is terminated with a coupling 150 to which a flexible connection leading to the gas space of a transport container may be attached. By such connections the gas evolved from both pumps 130 45 and 170, when being primed, is adapted to be conveyed to the gas space of vessel 10. Vessel 10, which is normally intended for closed operation, is accordingly provided with a safety valve 100.

50 The supply circuit 22 has an associated auxiliary container 24, together with heating and vaporizing coils, arranged substantially as shown in the system of Fig. 1. Here no automatic pump control is provided, as the auxiliary container 55 may be relatively large and hand control of the pumps 130 and 170 relied upon. In effecting such control, the pumps however are started and stopped substantially simultaneously. Since the container 11 is here operated under pressure, 60 the upper limit of which is maintained by the safety valve 100, the priming of the pumps need not be provided for other than initially. Hence the priming valves 162', 181 and 182 are preferably manually operated valves, although such valves may be arranged to be automatically operated if desired. The gas material from container 24 when heated and vaporized is normally discharged to service means through a meter, as indicated at 32.

70 When it is desired to fill the container 11, the valve at 201 is closed while that at 181 is opened. Then the pumps 130 and 170 are manually started, and the charge supplied through connection 14 (valve 14' having been opened while that at 75 12' is closed) is then passed successively through

the pumps 130 and 170 and discharged at a desired pressure into the vessel 10 at the top. The priming of the pumps may be necessary for filling, if this operation is to take place at the end of a time when the pumps have stood idle for a relatively long interval. For this purpose, valves 162', 162'' and 181 may be temporarily opened and valve 182 closed. As soon as liquid begins to pass, valves 162' and 162'' are again closed and valve 182 opened. The liquid then 10 passing from pumps 130 and 170 flows at the desired pressure and passes into the vessel 10.

In the modification shown in Fig. 3, the oxygen storage means connected to the service mains is not of liquid phase type but of the gas phase 15 type. In such case, the head of pressure carried in the storage means may be at a relatively high value, for example, at a value of 2000 p. s. i. gauge. The arrangement of pumps employed is accordingly one adapted to pump against such high head. To this end the liquid pump for transferring the liquid from the liquid storage container, such as shown at 11, is a reciprocating pump arranged to force liquid against such pressure. A suitable reciprocating pump adapted for this service is shown in copending application, Serial No. 369,023, filed December 7, 1940, in the name of O. A. Hansen. The arrangement utilizing such pump illustrated in Fig. 3, while shown as used in a stationary installation, is also adapted to be mounted on a truck or vehicle for transport service.

Here inner vessel 10 has a spaced outer vessel 11 that encloses an insulating space, as above described. A liquid inlet and withdrawal connection is provided at 12 and has a control valve 12'. Such connection leads from the outlet of a low pressure liquid transfer pump 13, which again is preferably of the rotary type and arranged as in Fig. 1. A valve controlled branch withdrawal line 12b also leads from the line 12 to the inlet of pump 13 which is utilized when pump 13 is employed as a fore pump supplying liquid to the second stage pump 175. A connection 12x controlled by a valve 12'' is also provided adapted to be connected, if desired, to the gas space of the transport container for priming purposes.

From the outlet of pump 13, a discharge conduit 16 (having a control valve 16') leads to the inlet of a reciprocating high pressure second-stage pump, here denoted 175. The discharge from this latter pump passes through conduit 185 and then into a connecting conduit 220 that leads to a vaporizing coil 223. This latter has an outlet conduit 221 that leads to a bank of gas phase receivers 224 that are floatingly attached, that is, they are in constant communication with conduit 221 and serve as accumulators or supply reservoirs, dependent upon conditions of demand and supply. A branch conduit 222 leads to a service main through a regulating manifold, as shown at 31, and a metering device, as shown at 32. A pressure controlled switch 300 for automatically starting and stopping the motor 176 which actuates pump 175 is provided in communication with conduit 222, the electrical connection from switch 300 to the motor 176 being shown generally at 176a.

The connection 185 is arranged to lead to the gas space of vessel 10 and has therein an automatic priming valve 186. Such valve is preferably automatic, as above described, or may be electromagnetically actuated; a solenoid for such purpose being shown at 186'. This valve is hence

5 automatically opened when the pump 175 starts and closes when liquid begins to pass. The gas discharged by the pump 175 when being primed discharges into a closed space, i. e., the gas space of vessel 10, an excessive pressure therein being prevented by means of a safety valve 100. A by-pass having a control valve 184 may be provided for manually priming the pump, if desired.

In the modification shown in Fig. 4, an arrangement is employed which is substantially a cold converter system of relatively high capacity and adapted to service loads that make relatively great demands and require substantially instantaneous response. Transfer pumps of both low pressure and high pressure types are incorporated at points where accelerated liquid flow is required, also gas pumps may be used.

In the arrangement an inner vessel 10' is surrounded by a vessel 11', which is spaced therefrom for insulating purposes. The vessel 10' here provided is designed to withstand relatively high pressures, and has a liquid filling and withdrawal connection 12, provided with valves 12' and 12'' therein and attached to the outlet of a transfer pump 13. The latter has an inlet connection 14 terminating with a coupling 15 for receiving a liquid charge that is to be transferred to the vessel 10'. A priming connection 12x is also provided, as in Fig. 1. Communicating with connection 12 is another connection 16 having a valve 16' and leading to the inlet of a high pressure liquid transfer pump 177 which is preferably of the reciprocating type, like the pump 175, above described. Such pump is arranged substantially as in Fig. 3 and has an actuating motor 178. Here a discharge conduit 187 leads from the outlet of pump 177 and discharges into vaporizing coils 227 and 227' that discharge in a supply main 230. This main has a bank of gas receiving vessels 224 floatingly attached and a connection 222 leading to a service main through a regulating manifold 31 and a metering device 32, as in the other modifications. An automatic control for pump 177 is also preferably provided and here comprises a pressure controlled switch 300 and priming valve 186, as in Fig. 3. The latter is arranged to control a priming connection 188 that leads to container 11'. A connection 189 also leads from the gas space of container 11' to a heating coil 229 which is arranged to discharge into the inlet of a suitable gas pump 240, which discharges into the supply main 230; a carbon ring pump, such as disclosed in copending application, Serial No. 409,626, filed September 5, 1941, in the name of G. J. Boshkoff, being an example of a suitable gas pump. An automatic by-pass valve 241 about the pump is advantageously provided.

60 Here vessel 10' in container 11' is a relatively thick-walled or pressure vessel. Hence the liquid therein may be and normally is under considerable pressure in order that liquid may be withdrawn and supplied to the pump 177 under a pressure sufficient to impart a desired degree of subcooling. To this end, provision is made for quickly vaporizing a desired amount of liquid to supply the pressure without at the same time unduly heating the liquid in the vessel 10'. According, a liquid withdrawal and heating connection is provided, which, in this instance, preferably includes a liquid transfer pump, which because of its low pressure service may well be a rotary pump. This is here indicated at 210 dis-

posed in a conduit circuit 211 that has one end leading from the bottom of vessel 10' into the pump 210. The other end portion leads from the discharge of the pump 210 into the gas space of vessel 10' and includes a vaporizing coil 212. In this arrangement, the pump 210 is normally primed at all times and when started withdraws liquid from the vessel 10' and the liquid is vaporized in coil 212. In this manner, a pressure of desired value, limited of course by safety valve 100, obtains in the vessel 10'. It is preferable, however, to associate with the system another pressure controlled switch responsive to the pressure in vessel 10' for actuating gas pump 240. This is here shown at 250 attached to conduit 189.

The switch 250, which controls the gas phase pump 240, is arranged to start pump 240 operating through the electrical connection 240a whenever the pressure in vessel 10' exceeds a predetermined value (less than that for which safety valve 100 is set). Pump 240 then operates to compress the gas and transfer it from vessel 10' to the supply conduit 230, the gas pump being automatically stopped when the pressure in vessel 10' falls to a predetermined low value.

In the event the pressure in vessel 10' tends to fall to a still lower value, then it is advantageous to provide still another automatic pressure responsive controlling switch which may be connected to the motor of pump 210. The switch means is here indicated at 260 connected to fluid circuit 211, an electrical connection for controlling the operation of pump 210 being shown diagrammatically at 210a. Thus, it is seen that pump 210 may be automatically started to build pressure in vessel 10' whenever the pressure therein drops below the second-mentioned predetermined value and automatically stops the same when this value is attained.

The reserve of gas material in the receivers 224 is, of course, maintained by the pump 171 which is automatically controlled by the switch at 300 connected through electrical circuit 178a with the rotor 178. Thus the system here provided is seen to be pipeline demand controlled, since the pressure which actuates the switch at 300 is subject to the fluctuations of the pipeline pressure.

Details of switches and circuits for effecting the above controls are here omitted, as any suitable system thereof known to the prior art may be employed. A suitable arrangement, however, is described in the copending application of G. J. Boshkoff, *supra*.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described our invention, what we claim as new and desire to secure by Letters Patent is:

1. In a system for converting a liquefied gas into a vapor for industrial use, the combination with a heat insulated container adapted for holding a supply of said liquefied gas, of pumping means associated with said container and having liquid phase connections leading therefrom, a gas consuming system including servicing connections and heating and vaporizing means connected to be supplied from said container, means

for holding a reserve of said gas material under pressure in fluid communication with said consuming system, and means for maintaining a desired pressure in said reserve holding means.

- 5 2. In a system for converting a liquefied gas into a vapor for industrial use, the combination with a heat insulated container adapted for holding a supply of said liquefied gas, of pumping means associated with said container and having liquid phase connections leading therefrom, a gas consuming system including servicing connections and heating and vaporizing means connected to be supplied through said pumping means, means for holding a reserve of said gas material under pressure in fluid communication with said consuming system, and means for controlling the operation of said pumping means whereby a desired reserve may be maintained in said reserve holding means.
- 10 15 20 3. In a system for converting a liquefied gas into a vapor for industrial use, the combination with a heat insulated container adapted for holding a supply of said liquefied gas, of pumping means associated with said container and having liquid phase connections leading therefrom, a gas consuming system including servicing connections and heating and vaporizing means connected to be supplied through said pumping means, means for holding a reserve of said gas material under pressure in fluid communication with said consuming system, and means for controlling the operation of said pumping means whereby a desired reserve may be maintained in said reserve holding means.

means, an auxiliary container in fluid communication with said consuming system for holding a reserve of said gas material in both liquid and gas phases under pressure, means for regulating the pressure of gas material supplied to said consuming system, means for actuating said pumping means, and means for effecting preferential withdrawal of gas phase from said auxiliary container when a predetermined pressure is exceeded.

7. In a system for converting a liquefied gas into a vapor for industrial use, the combination with a heat insulated container adapted for holding a supply of said liquefied gas, of pumping means associated with said container and having liquid phase connections leading therefrom, a gas consuming system including servicing connections and heating and vaporizing means connected to be supplied through said pumping means, an auxiliary container connected to said consuming system and adapted for holding a reserve of said gas material in both liquid and gas phases under pressure, and float actuated means connected to said auxiliary container for automatically operating said pumping means whereby the level of the liquid in said auxiliary container may be maintained.

8. In a system for converting a liquefied gas into a vapor for industrial use, the combination with a heat insulated container adapted for holding a supply of said liquefied gas, of pumping means associated with said container and having connections leading thereto for transferring liquid into and withdrawing the same from said container, a gas consuming system including distributing conduits and interposed heating and vaporizing means connected to said container, means for holding a reserve of said gas material under pressure in continuous communication with said consuming system, and means for automatically operating the liquid withdrawal pumping means for maintaining a desired reserve in said reserve holding means.

9. In a system for converting a liquefied gas into a vapor for industrial use, the combination with a heat insulated container adapted for holding a supply of said liquefied gas, of pumping means associated with said container and having connections leading thereto for transferring liquid into and withdrawing the same from said container, a gas consuming system including distributing conduits and interposed heating and vaporizing means connected to said container, an auxiliary container connected to said system for holding a reserve of gas material in both liquid and gas phases under pressure, means for regulating the pressure of said system, means for effecting preferential withdrawal of gas phase from said auxiliary container when a predetermined pressure is exceeded therein, and liquid level actuated means associated with said auxiliary container for automatically operating the liquid withdrawal pumping means whereby a desired reserve of material in the liquid phase is maintained in said auxiliary container.

10. In a system for converting a liquefied gas into a vapor for industrial use, the combination with a heat insulated container adapted for holding a supply of said liquefied gas, of pumping means associated with said container and having connections leading thereto for transferring liquid into and withdrawing the same from said container, a gas consuming system including distributing conduits and interposed

heating and vaporizing means connected to receive liquid phase withdrawn from said container, an auxiliary container, branched connections leading from said system to the gas space of said auxiliary container, one of said branches being adapted to supply liquid from said pumping means to said auxiliary container and effect a partial condensation of the gas phase therein, said other branch being provided with automatic regulating means whereby a preferential withdrawal of gas phase is effected and supplied to said system, means for withdrawing liquid from said auxiliary container upon demand in said system, means for regulating pressure of the gas phase supply in said system, and means for operating said pumping means for maintaining a desired reserve in said auxiliary container.

11. In a system for converting a liquefied gas into a vapor for industrial use, the combination with a heat insulated container adapted for holding a supply of said liquefied gas, said container having a relatively heavy-walled inner vessel, of a gas consuming system including service connections and heating and vaporizing means connected to be supplied from said container, pressure building means including a heating coil connected to said heavy-walled vessel at points both above and below the normal liquid level therein, pumping means associated with said pressure building means and arranged to withdraw liquid from said container and accelerate the rate of pressure building, and pressure responsive means for controlling the operation of said pumping means.

12. In a system for converting a liquefied gas into a vapor for industrial use, the combination with a heat insulated container adapted for holding a supply of said liquefied gas, said container having a relatively heavy-walled inner vessel, of a pressure building means associated with said container and having a vaporizing means therein, a liquid pump associated with said pressure building means for accelerating the action thereof, additional pumping means associated with said container and having connections for withdrawing liquid therefrom, a gas consuming system including servicing connections and interposed heating and vaporizing means connected to said additional pumping means, and automatic means for controlling said additional pumping means in response to a condition in said consuming system.

13. In a system for storing and converting a liquefied gas into vapor for industrial use, a main heat insulated liquid storage container, a gas consuming system embodying servicing connections, heating and vaporizing means, and auxiliary storage means, pumping means and fluid conduits for delivering liquid from said main container to said consuming system, and means for controlling the operation of said pumping means to maintain a desired minimum pressure in said auxiliary storage means.

14. In a system for storing and converting a liquefied gas into a vapor for industrial use, a heat insulated main storage container for holding a supply of said liquefied gas adapted to be maintained at a relatively low pressure, a gas consuming system embodying servicing connections and vaporizing and heating means, pumping means and fluid conduits for supplying gas material from said container to said consuming system at increased pressure, means for holding a reserve of the gas material under pressure

connected with said consuming system, and means for automatically controlling said pumping means to maintain a desired pressure in said reserve holding means above that of said main container.

15. In a system for storing and dispensing a liquefied gas and converting it into vapor for industrial use, a main heat insulated liquid container adapted to be maintained at a relatively low pressure, an auxiliary smaller liquid container, fluid conduits and pumping means for delivering liquid from said main container to said auxiliary container at higher pressure, vaporizing and heating means connected with said auxiliary container, and servicing connections for supplying consuming apparatus through said vaporizing and heating means.

16. In a system for storing and dispensing a liquefied gas and converting it into vapor for industrial use, a main heat insulated liquid container adapted to be maintained at a relatively low pressure, a smaller liquid container adapted to maintain a reserve of gas material in both the liquid and gas phase at a higher pressure suitable for gas consumption apparatus, fluid conduits and pumping means for delivering liquid from said main container to said auxiliary container, servicing connections for supplying consumption apparatus, means for effecting preferential withdrawal of gas phase from said auxiliary container for use when a predetermined pressure is exceeded, means for controlling the operation of said pumping means to maintain a predetermined quantity of liquid in said auxiliary container, and vaporizing and heating means connected with said auxiliary container and servicing connections.

17. In a system for storing and converting a liquefied gas into a vapor for industrial use, the combination with a heat insulated container adapted for holding a supply of said liquefied gas, of a gas consuming system including servicing connections and vaporizing and heating means connected to be supplied from said container, pumping means for delivering liquid from said container to said consuming system, gas receiver means in fluid communication with said system adapted to hold a reserve of gas under pressure sufficiently high for the consumption apparatus to be supplied, and means responsive to the pressure in said system for controlling the operation of said pumping means to maintain such pressure above a predetermined value.

18. In a system for storing and converting a liquefied gas into a vapor for industrial use, the combination with a heat insulated container adapted for holding a supply of said liquefied gas, of a gas consuming system including servicing connections and vaporizing and heating means connected to be supplied from said container, pumping means for delivering liquid from said container to said consuming system, a gas compressor and conduit means arranged to deliver excess gas accumulation in said container to said system, gas receiver means in fluid communication with said system adapted to hold a reserve of gas under pressure sufficiently high for the consumption apparatus to be supplied, and means responsive to the pressure in said system for controlling the operation of said pumping means to maintain such pressure above a predetermined value.

19. In a system for supplying under pressure a highly volatile liquefied gas material having

a boiling point temperature at atmospheric pressure below 273° K., a storage container for the liquid, a pump for delivering the liquid under such pressure for use having an intake connected

5 to said storage container, a main delivery line for said pump, an auxiliary discharge line connected to said pump and leading to a point of relatively low pressure with respect to the normal delivery pressure of said pump, an automatically operable valve in said auxiliary discharge line responsive to pressure therein, said valve being constructed and arranged to be open upon initial starting of said pump during generation of substantial quantities of gas from the liquid

15 while said pump is being cooled by the material passing therethrough and to close by the development of a predetermined pressure in the pump discharge.

20. In a system for supplying under pressure

20 a highly volatile liquefied gas material having a boiling point temperature at atmospheric pressure below 273° K., a source of supply of such liquid, a pump for delivering the liquid under such pressure for use having an intake connected 25 to said source of supply, a main delivery line for said pump, a check valve therein preventing back flow, an auxiliary discharge line connected to said pump in advance of said check valve and leading to a point of relatively low pressure with

30 respect to the normal delivery pressure of said pump, an automatically operable valve in said auxiliary discharge line responsive to pressure in the pump discharge, said valve being constructed and arranged to close when substantial pressure is developed by the passage of liquid into the auxiliary discharge line causing the pump to deliver the liquid to said main delivery line and to remain open when no liquid is being delivered by said pump.

40 21. In a system for storing and converting a liquefied gas into a vapor for industrial use, a heat insulated storage container for holding a supply of said liquefied gas, a gas consuming system embodying servicing connections and

45 vaporizing and heating means, pumping means and fluid conduits for delivering liquid from said container to said system, pressure regulating means in said servicing connections, a gas compressor and conduit means arranged to deliver excess gas accumulation in said container to said system at a point on the upstream side of said pressure regulating means, and means responsive to pressure in said system for controlling the operation of said pumping means to maintain a predetermined pressure in the system in advance of said regulating means.

22. In a system for converting a liquefied gas into a vapor for industrial use, the combination with a heat insulated container having an inner

60 vessel adapted for holding a supply of said liquefied gas, of a gas consuming system including service connections and heating means, pressure building means including a heating coil connected to said vessel at points both above and below the normal liquid level therein, pumping means and fluid conduits for supplying gas material from said vessel to said system, means for automatically controlling said pumping means

65 responsive to pressure in said service connections, and means responsive to the pressure of vapor above the liquid in said vessel for regulating the flow of liquid to said pressure building means.

70 23. A method of handling a gas material hav-

ing a boiling point temperature at atmospheric pressure materially less than 233° K., which comprises maintaining a supply of such gas material in the liquefied state in a heat insulated container, intermittently withdrawing material in the liquid state from said container and delivering such material at an elevated pressure for use as required to meet a service demand, mechanically withdrawing material in the gas phase from the accumulation thereof within said 10 container when said gas phase has attained a

pressure of a selected high value, elevating the pressure of said withdrawn gas phase to at least a predetermined service value, and continuing such withdrawal of gas phase to reduce the pressure of the gas phase in said container, and stopping the withdrawal of said gas phase when a selected low value of the pressure of the gas phase being withdrawn is attained.
